UNITED STATES PATENT OFFICE.

JAMES L. BRICE, OF ABERDEEN, WASHINGTON.

SHAVING-BRUSH.

1,230,660.

Specification of Letters Patent. Patented June 19, 1917.

Application filed August 1, 1916. Serial No. 112,587.

To all whom it may concern:

Be it known that I, JAMES L. BRICE, a citizen of the United States, residing at Aberdeen, in the county of Grays Harbor and State of Washington, have invented new and useful Improvements in Shaving-Brushes, of which the following is a specification.

This invention relates to shaving brushes and it consists in the novel features herein-after described and claimed.

An object of the invention is to provide a brush of collapsible form which is convenient to carry and which includes a casing slidably mounted with relation to a block the block carrying the bristles of the brush. The block may be moved within the casing whereby the bristles are inclosed within the same and the block may be moved to a position at the end of the casing whereby the bristles are projected beyond the edge of the same and may be used for applying lather. The casing is provided at the sides with slots having enlargements at their ends and spring pressed pins are mounted in the block and are adapted to move along the grooves, the said pins having shoulder portions adapted to enter the enlargement whereby the block is temporarily held at a fixed position with relation to the casing.

In the accompanying drawing:—

Figure 1 is a perspective view of the shaving brush showing the arrangement of parts when the bristles are inclosed within the casing.

Fig. 2 is a detailed view of the block carrying the bristles.

Fig. 3 is a similar view of one of the pins.

The shaving brush includes a cylindrical casing 1 which is provided at its opposite sides with longitudinally disposed grooves or slots 2. Enlarged openings 3 are provided at the ends of the slots 2 and are adapted to receive the neck portions or pins hereinafter described. A cap 4 may be applied to either end of the casing 1 and the intermediate portion of the said cap is provided with a number of perforations 5.

A block 6 is arranged to slide within the casing 1 and the said block is provided at one end with a set of bristles 7. An opening 8 passes transversely through the inner portion of the block 6 and pins 9 are slidably mounted in the said opening. A coil spring 10 is located in the intermediate portion of the opening 8 and bears at its ends against the inner ends of the pins 9. The said

spring 10 is under tension with a tendency to normally hold the outer end of the pins 9 projected beyond the outer surface of the block 6. The pins 9 are provided at their outer portions with shoulders 11 and beyond the said shoulders the said pins are provided with necks 11' and reduced portions 12. The reduced portions 12 of the said pins may move along the slots 2 but the shoulder portions 11 of the said pins are of a diameter greater than the transverse dimension of the slot 2 and the diameter of the openings 3 consequently the said shoulder portions cannot enter the slots or the openings. The said neck portions 11' may enter the enlarged openings 3 at the ends of the slots 2 when the pins are brought into alinement or register with the said enlarged openings 3 but they cannot move along the slot 2. The casing 1 is closed at one end and open at its other end. When pressure is applied to the outer ends of the pins 9 they are moved in an inward direction with relation to the block 6 so that the reduced portions 12 are brought between the edges of the slot 2. The block 6 may then be moved toward the closed end of the casing 1 and when the pins 9 are in alinement with the openings 3 adjacent the closed ends of the said casing the tension of the spring 10 comes into play whereby the said pins are forced outwardly and the neck portions 11' engage in the said enlarged openings 3. Thus the block 6 is held within the casing 1 and the bristles 7 are housed within the same. The cap 4 may then be placed over the open end of the casing 1 and the bristles are effectually protected. The perforation 5 permits air to enter the interior of the casing whereby the bristles may dry in the event that they are inclosed while damp.

To extend the bristles 7 with relation to the casing 1 the pins are forced in an inward direction and then moved along the slots 2 until the said pins come in contact with the enlargements 3 adjacent the open end of the casing 1. The tension of the spring 10 then comes into play whereby the said pins are forced in an outward direction and their neck portions engage in the said enlarged openings 3. Thus the said bristles 7 are held in an extended position with relation to the casing 1 and may be freely used for making and applying lather.

From the foregoing description taken in conjunction with the accompanying draw-

ing, it will be seen that a shaving brush of collapsible form and simple and durable structure is provided and when not in use the bristles may be inclosed and the parts 5 collapsed so that the device occupies but small space and consequently may be readily packed for shipment or transportation.

Having described the invention what is claimed is:—

- 10 10 A shaving brush comprising a casing having slots located at its sides and provided with enlarged openings at the ends of the slots, a block slidably mounted in the casing and provided with bristles, pins slidably 15 mounted in the block, a spring located in the

block and bearing at its opposite ends against the inner ends of the pins, said pins having shoulders adapted to bear against the inner surface of the casing around the openings whereby the outward movement of 20 the pins is limited, said pins also having neck portions located beyond the shoulders and adapted to enter the said enlarged openings and being of greater diameter than the transverse breadth of the slots, said pins being further provided with reduced portions adapted to move along the slots when the pins are depressed.

In testimony whereof I affix my signature.
JAMES L. BRICE.
